PROPELLER TYPE VENTILATOR FAN

Walter L. Upson, Litchfield, Conn., assignor to
The Torrington Manufacturing Co., Torrington,
Conn., a corporation of Connecticut

Application June 21, 1940, Serial No. 341,659

12 Claims.

(Cl. 170—159)

This invention relates to improvements in propeller type ventilator fans, and more particularly to fans of the larger sizes, such as used for the ventilation of residences and other buildings. More specifically, the present improvements pertain to balancing and silencing features which are particularly applicable to fans of the noted types.

Two methods have been generally heretofore utilized in balancing the blade structure of propeller type fans; the first of these consists in removing a certain amount of the mass from one or more of the blades, as by grinding or the like, while the second method is usually practiced by displacement of one or several of the blades of the fan, to the end of altering the relation between adjacent blades in the plane of rotation, with the effect of varying the distribution of the weight of the blades about the axis of revolution of the fan. It is obvious that neither of these methods is fully satisfactory, in that a condition of true balance is often only approximated. For example, if too great an amount of metal is removed as by grinding incident to balancing, the blade area and shape are adversely affected. Similarly with respect to the method involving the bending of the blade or the supporting arm therefor, if the fan is very greatly out of balance this method can only approximate a full correction of the condition of unbalance. Each of the noted methods of balancing is time-consuming and expensive, and is not susceptible of any quantitative method of predetermining the extent of correction required in order fully to balance the fan.

It will be obvious that neither of the methods heretofore usually practiced is adaptable to most types of ventilator fans, which are usually constructed in the larger sizes, for example, in diameters of 24", 36" or even greater diameters. It is accordingly a major object of the invention to attain an improved method and structure for balancing fans of types in which the blade-carrying arms and blades are formed of more than the usual gauges of sheet metal, and which may be quickly and easily utilized in the balancing of fans without any appreciable deflection, distortion, grinding or other removal of metal of the blade.

Yet another object of the invention is attained in an improved means for reducing the noise transmitted by propeller type fans, which means is or may be practiced incidentally to the balancing of the fans, and which serves markedly to

reduce any tendency to resonance, and thus produces a more quietly operating fan.

Yet another object is attained in an improved balancing and silencing method and means which do not in any way affect the external appearance of either the blades or the spider arms, as is the case with certain balancing and silencing expedients heretofore employed.

A still further object of the invention is attained in an improved resonance-damping expedient, through the structural interconnection of the blades proper, and which is particularly adapted to propeller type fans characterized by a relatively small number of blades.

An important additional object is attained in a fan-mounted guard structure, which serves as a measure of protection against personal injury by tending to prevent casual introduction of fingers or clothing to the spaces between the blades; this object being conveniently realized by blade-interconnecting elements which also serve to dampen blade vibrations.

The foregoing and other objects will appear from the following detailed description of a presently preferred embodiment of the invention, considered in connection with the accompanying drawing, in which:

Fig. 1 is a front elevation of a three-blade ventilator fan to which the present improvements are applied; Fig. 2 is a fragmentary rear elevation of a center disc, one of the blade arms and a portion of the blade secured thereto; Fig. 3 is an enlarged fragmentary sectional elevation longitudinally of one of the blade arms and the connected blade, this view being taken in a plane normal to the intermediate area of the blade, and as viewed along line 3—3 of Fig. 1; Fig. 4 is a fragmentary section taken transversely of one of the blades and the associated blade arm, the location of this section being indicated by line 4—4 of Fig. 2; Fig. 5 is a fragmentary sectional elevation through and along a margin of one of the blades, as viewed along line 5—5 of Fig. 1, and Fig. 6 is a front elevation of a fan similar to that shown by Fig. 1, but illustrating a modified form of vibration dampening and blade guard structure.

Referring now by characters of reference to the drawing, there is shown by Fig. 1 a propeller type fan assembly, the features of which are susceptible of use in fans of a substantial range of sizes. The fan as shown embodies a relatively heavy metal center disc 10 provided with a central shaft opening (not shown), and into which is inserted a metal hub or hub sleeve 11 provided

with a retaining shoulder 11A and a swaged or spun over portion 12 through which the disc is secured to the hub. The fan assembly is mounted for rotation on a shaft 13 which is or may be of conventional arrangement, and which is usually, in fans of the noted type, belt-driven from a motor or other suitable prime mover (not shown).

In the disclosed example, consisting of a three-blade fan, the center disc 10 serves as a support for three blade arms 14. Each of these blade mounting elements is characterized by a planar portion 15, secured as by rivets 16 or the like, to the disc 10. Each of the arms is twisted as at 17 in a zone slightly radially beyond the disc 10, so as to provide the predetermined pitch angle of the blade carried by the associated arm. Beyond the twisted portion is found an outer planar portion 20 to which is secured the blade 21, as by the rivet or like elements 22.

Each of the blades may be broadly designated as of shovel form, characterized by a substantially rectangular outline, with rounded outer corners, through the outer portion of the blade, when viewed in plan; the inner end of each blade being of a substantially regular arcuate contour as shown. The exact shape of blade is, however, not material to the present improvements, but in order further to describe for completeness, the blades illustrated, it may be noted that each thereof is characterized by a forwardly turned lip 23 on the outer leading edge portion of the blade, an intermediate, substantially planar portion 24, and a relatively sharply forwardly turned part or trailing margin 25. The leading and trailing portions 23 and 25 respectively are demarcated from the intermediate portion as by substantially rectilinear zones 26 and 27, each of these zones of folding or bending extending at a slight acute angle to a radius on the axis of shaft 13, from which it results that each blade presents a channel which is of a trend at an acute angle to a radius, in accordance with the disclosure and claims of Letters Patent No. 2,021,707 and 2,072,-322 of this applicant, issued respectively November 19, 1935, and March 2, 1937.

The present improvements contemplate the optional provision in each of the blades, of a substantially radial groove, flute or channel 30, as shown by the section of Fig. 4. When employed, this groove is preferably die-formed in the blade at the time of shaping or bending, and is arranged so that the groove or flute is presented as a radial depression in the rear side of the blade, resulting in a radial projection on the forward side or surface of the blade. By preference, the grooves or flutes 30 each extend from a point about midway of the length of the blade, fully to the inner end thereof.

Each of the spider arms or blade mounting elements is, by preference, similarly characterized by a longitudinally fluted portion or channel formed in the arm at the time of stamping or shaping the arm, the flutes, channels or grooved portion of each of the blade arms being indicated at 31. It is to be noted as a preference that the grooves or flutes of the several spider arms, extend the full length thereof and approximately along median lines of the respective arms. As best appears from Figs. 3 and 4, the assembly of each blade and the associated arm is such that the companion grooves 30 and 31 are relatively oppositely disposed, i. e., with the two grooves facing each other, so that when the groove 30 is utilized, the two grooves 30 and 31 coact to form a

radial pocket, channel or tube, between each blade and the arm to which it is assembled, this relation best appearing from Figs. 3 and 4 wherein the pocket or radial chamber is indicated at 32.

The tubular chamber or pocket 32 serves, according to the presently described means of balancing a fan, as an elongate chamber for the reception of units of a balancing material, and according to preference, this material consists of some suitable rod stock, such as a steel wire or like material, which may be easily cut into desired lengths and thus arranged in units of desired weight.

It may be here noted that the insertion of units of a balancing material, such as indicated at 33, tends markedly to reduce any tendency to resonance which might otherwise be exhibited by the blade. The vibration-damping effect of the pellets or units in the radial channel or pocket 32, serves to impart a "dead" sound to the blade whose weight has been augmented by the balancing material. It will be noted further that the fact of arriving at a good degree of balance by reason of the expedients heretofore described, serves of itself, to minimize unbalanced conditions of the fan as a whole, and in so doing, serves to produce a more quiet running fan than would otherwise be the case.

A further, in some respects preferable, balancing provision is best shown by Figs. 2 and 3, as including one or more grooves 34 transverse of the blade arm, the transverse flutes, channels or pockets being best observed from the projections 35 (Fig. 2) resulting from depressions of the blade-engaging face of the arm. These channels may selectively or together be utilized to contain predetermined lengths or weights of the balancing units 33, which will serve not only their primary balancing effect, but will exhibit a secondary effect of reducing blade resonance.

In order still further to assure quiet operation of the fan as an operating unit, and to minimize resonance effects of its blades, it is preferred structurally to tie together the leading edges of the several blades, one expedient for this purpose being shown by the tie rings 40. Each of these is preferably formed as a single annular piece, preferably of heavy wire or rod stock of endless form, each ring 40 whether one or more than one is utilized, being welded or otherwise firmly secured to the leading margins of the several blades. One example of such securing is shown by the weld zone 41, as best appears in Fig. 5.

In a fan utilizing blades of the general form of Fig. 1, it has been found that the more sharply curved upturned trailing portions 25 serve markedly to damp out any blade vibrations which might otherwise tend to occur in the trailing halves of the blades. Accordingly it is more desirable to secure the resonance damping elements, such as one of the rings 40, to the leading edges of the blades, as shown. This arrangement has the further advantage of creating less adverse air disturbance and turbulence effects in the slip stream from the fan.

As a result of experiments with tie elements located in securing to different radial zones of the blades, it has been found that a member such as ring 40, is most advantageously disposed in securing to an intermediate portion of the leading edge of the blade, i. e., neither too close to the inner end of the blade, nor too close to the zone of securing of blade and blade arm, yet not too close to the outer periphery or tips

of the blades. The latter because of their higher lineal velocity, will be affected to a greater extent in their displacement characteristics, than will the intermediate portions of the blades to which each of the rings is secured as in the disclosed example.

It will be understood, of course, that instead of a single or multiple arrangement of unitary ring elements such as 40, separate tie elements may be employed for the purpose of interconnecting the various blades. One such arrangement is shown by Fig. 6, wherein three separate arcuate rods such as 50, serve as tie elements between the blades, each member 50 serving to bridge the leading edge of one blade and the trailing edge of an adjacent blade, securement of the tie rods being effected as by welding in the zones 51 and 52, after the manner of the weld zone 41 (Fig. 5) or by any other suitable fastening expedient.

The manner of application, and the resonance-damping effect of the tie element or elements such as 40 or 50, will now be at once apparent to those skilled in the art, without requiring any description of assembly or function.

The manner of use of the wire or rod stock or other material for the purpose of perfecting the balance of the fan will, similarly from foregoing description, be apparent to those skilled in the art of balancing propeller type fans. The fan rotor, being the assembly of blades, blade arms and center disc, or in lieu of the arms and disc, a spider element, may be tested by methods well known in the art, wherein the degree and nature of unbalance is quantitatively determined. Following this determination, balance weights may be tentatively applied to the fan. The selected length of the rod or wire unit is then inserted, either into the upper end of the pocket 32, or the end of channel 34, or both. The balance may then be redetermined, and if minor adjustment is necessary, the location of the balancing unit may be radially shifted in the pocket 32, by moving it inwardly or outwardly thereof, or may be shifted or substituted by another unit in groove 34. With the optimum location of the correct weight of the unit or units of balancing material such as 33 in one or more of the grooves, it is preferred that the location of the balancing unit or units be fixed by upsetting, deforming, or inwardly displacing spaced portions of the metal defining at least one of the grooves 30, 31 or 34. In any event it is preferred that the inner end of the chamber 32, if occupied, be inwardly deflect- ed as shown at 42. Similarly, the outer end portion of the groove formed in the spider arm, for example as shown at 43 may be inwardly depressed or deformed so as to constrict the ends of the radial pocket or chamber 32. It will also be found desirable in some cases, to depress an intermediate portion of one or more of the grooves, as indicated at 44, which upset portion of the metal serves to retain the unit of balancing material in its intended position between the blade and blade-supporting arm. It will have appeared of course that it is desirable thus to fix the location of the balancing units in such of the chambers 32 or 34 to which they are applied, after the correct amount and positioning of the balancing metal has been experimentally determined.

Referring further to the fan construction, the fans of the type herein described, to illustrate the invention, were first constructed by utilizing a single blade arm for each blade, and so operated satisfactorily. It was thereafter deter-

mined that the provision of two parallel blade arms for each blade, enhanced the rigidity of blade mounting, and tended further to reduce blade resonance and vibration. The improved arrangement is illustrated by Fig. 1, wherein the blades are each disposed between paired cooperating blade arms, the forwardmost arm being indicated at 14 and the rear arm at 14A, the latter being somewhat longer, and by preference being the one provided with the groove-forming ribs such as 35. It will be noted as optional whether or not the channels for reception of the balancing units 33, be formed in part by grooving the blade. Although this offers some advantages, the chamber 32 or groove 34 may be formed solely in the blade arm, for example arm 14A.

By way of further discussion of the blade interconnection, serving the dual purpose of a vibration-dampening agency and a fan-mounted guard, both purposes are admirably attained by locating each of the rings 40 eccentrically of the fan, with the ring centers diametrically opposed or offset. Thus by using two or more such rings a balanced relation of the structure may be attained, and the spaces between blades well guarded. Obviously a single ring, concentrically arranged on the fan, will serve a similar purpose, but less effectively as a guard, as is true of the kindred structure of Fig. 6.

It will have appeared from the foregoing description that the various features of the invention serve admirably to attain each and all of the objectives hereinabove expressly pointed out, as well as others implied from the ensuing description.

Although the invention has been described by making a somewhat specific reference to the various parts of a preferred embodiment, this description is to be understood in an illustrative and not in a limiting sense, since many changes may be made in the parts, their combinations and arrangements, without departing from the full intended scope of the invention as defined by the claims hereunto appended.

45 I claim as my invention:

1. In a propeller type fan, a spider including a spider arm, a blade assembled to the arm, the blade and arm having depressed portions in their adjacent areas, the depressed portions coacting to form a substantially closed chamber between the assembled blade and arm, and an element of balancing material laterally confined under compression in said chamber.

55 2. In a propeller type fan, a spider including a spider arm, a fan blade assembled to said arm, the blade and arm each being grooved or fluted and the elements being assembled with their grooves or flutes in opposed relation whereby the assembled blade and arm coact, in their grooved portions, to form an elongate, open end chamber, and an elongate element of fan-balancing material disposed with at least a portion thereof in compressed condition for its retention in said chamber.

60 3. In a propeller type fan, a spider including a spider arm element, a blade element assembled to the arm element, one of said elements being grooved or fluted to form with the other element, an elongate open end chamber adapted for the reception of an element of fan-balancing material, a rod-like counterbalancing element in said chamber, and the ends of the grooved portion of at least one of said elements being so shaped as to retain the counterbalancing element in said chamber.

4. In a fan construction, a spider arm, a blade assembled thereto, the blade and arm being formed in adjacent areas to provide a tubular chamber therebetween, an elongate element of fan balancing material in said chamber, and portions of one of the chamber-forming elements being shaped to prevent shifting of the element of balancing material in the chamber after the fan assembly is brought to balanced condition.

5. A fan construction for the reduction of resonance, including a spider having a plurality of spider arms, a fan blade assembled to each of said arms, a radial groove or flute formed in each blade adjacent the spider arm and coacting therewith to form an elongate tubular chamber, an element of balancing and resonance-reducing material in one or more of said chambers, with the groove for said element constricted to retain the element therein, and an annular member secured to and carried by the leading edges of the several fan blades for the further reduction of blade resonance.

6. In a propeller type fan, a construction for the reduction of blade resonance including companion opposed radial grooves formed in each of the spider arms and opposed companion grooves in each of the fan blades, the grooves extending in a general radial direction and the grooves of each spider arm and associated blade coacting to form a tubular chamber, a resonance-reducing element in one or more of the chambers, certain of the chamber-forming portions being constricted adjacent the element therein for fixing the position of the element in the chamber, and a ring secured to the leading edges of each of the blades, radially outwardly of the spider and substantially inwardly of the periphery of the fan.

7. In a propeller type fan, blades and mounting means therefor, including an arm along each blade, means for minimizing blade resonance, provided by a radial channel formed along each blade, adjacent the arm, a rod element having a press fit for its retention in the tubular chamber provided by the channel and blade arm, and a ring element secured to the leading edges of the several blades of the fan, the ring element being of a diameter to dispose it radially outwardly of the zone of securement of the blade arms to the blades.

8. In a propeller type fan, a plurality of blades, means for mounting each of the blades on a shaft

5 or the like for rotation, said means including a blade-carrying arm secured to the blade, the arm being characterized by a channel depressed in a face portion of the arm, the axis of which lies across the arm and the open side of the channel being presented toward the blade, and coacting with the blade to form a chamber adapted for the reception and retention of a unit of balancing material, said chamber being characterized by a constricted portion, and a unit of balancing material in the chamber and fixedly positioned therein by said constricted portion.

9. The combination stated in claim 8, further characterized by a channel the axis of which lies along the blade-carrying arm, the channel opening into the blade-engaging face of the arm, and a unit of balancing material in the channel, the channel and adjacent blade portion coacting in assembly to enclose said unit, and having a portion of the material near the unit, deformed to prevent shifting of the unit in the channel.

10. In a propeller type fan, a plurality of spaced blades, blade mounting means by which the blades are supported for rotation, and a combined fan guard and resonance-damping structure comprised of a plurality of rings, said rings being secured to and carried by the blades, and eccentrically mounted on the fan with respect to the axis of rotation.

11. In a propeller type fan, a plurality of spaced metal blades, blade mounting means by which the blades are supported for rotation, and a combined fan guard and resonance-damping structure comprised of a plurality of rings, said rings being secured to and carried by the blades, and eccentrically mounted on the fan with respect to the axis of rotation, a pair of said rings being so positioned with respect to each other and with respect to the fan, in a manner to maintain the running balance of the fan.

12. In a propeller type fan, a plurality of blades, means for mounting the blades for rotation, as on a shaft, and means bridging the spaces between the blades and including a pair of ring elements carried by the blades, intermediate portions of the ring elements being mounted with their centers on diametrically opposite sides of the axis of revolution of the fan to preserve the running balance of the fan, and in overlapping relation to extend the blade-guarding effect of the rings.

WALTER L. UPSON.
